UNITED STATES PATENT OFFICE.

ARTHUR TREVE HOLMAN, OF CAMBORNE, CORNWALL, AND KENNETH JAMES HOLMAN, OF CARBIS BAY, CORNWALL, ENGLAND, ASSIGNEES TO HOLMAN BROTHERS LIMITED, OF CAMBORNE, CORNWALL, ENGLAND, A BRITISH COMPANY.

FORGING MACHINE.

Application filed May 1, 1924. Serial No. 710,326.

To all whom it may concern:

Be it known that we, ARTHUR TREVE HOLMAN and KENNETH JAMES HOLMAN, subjects of the King of England, residing in 5 Camborne, Cornwall, England, and Carbis Bay, Cornwall, England, have invented certain new and useful Improvements in Forging Machines, of which the following is a specification.

10 This invention consists in improvements in or relating to forging machines particularly adapted for shaping and sharpening the working faces of bits for rock-drills and for boring or drilling tools.

15 One object of the invention is to provide a machine which will combine compactness with a very considerable holding or gripping pressure for the drill-bit.

The invention is applied to a known type 20 of machine in which a pair of jaws is provided one of which is movable by means of a piston-and-cylinder device towards and away from the other. The drill-bit or the like is held between these jaws, and a reciprocating dolly or forging hammer is provided to operate on the end face of the bit or the like while it is held between the clamping jaws. There may also be associated with the jaws a part which serves to 25 forge or shape parts of the drill-bit before end-sharpening or shaping is effected by means of the dolly.

For the sake of brevity herein machines 30 of this class will be referred to throughout 35 the specification and claims as drill-sharpening machines although it will be understood that the machine may be employed for any forging operation of which such machines are capable.

40 According to one feature of the invention a drill-sharpening machine of the type described is characterized by the combination of the movable jaw with two pistons and cylinders arranged in tandem, the pistons 45 being both carried on a single piston-rod and serving jointly to actuate the movable jaw to close it on to or towards its companion jaw.

The invention also includes other details 50 of construction, all of which will be more clearly understood from the following description, given by way of example, of one

preferred construction according to the invention, which is illustrated in the accompanying drawings wherein—

55

Figure 1 is a side elevation of the machine viewed from the left of Figure 2 with the sizing die and its associated parts omitted for the sake of clearness;

Figure 2 is a section on the line 2—2 of 60 Figure 1;

Figure 3 is a section on the line 3—3 of Figure 1 with a sizing die and holding means therefor shown in position but with the dolly hammer and its co-operating parts omitted; 65 and

Figure 4 is an elevation partly in section of the double piston-device for the movable jaw.

Like reference numerals indicate like parts 70 in the several figures of the drawings.

On a base or pedestal 10 there are mounted two cylinders 11 and 12 co-axially arranged vertically in tandem. Working in the cylinders 11 and 12 are two pistons 13 75 and 14 respectively both mounted on a single piston-rod 15 which slides through the upper wall of the cylinder 11. The piston 14 is secured to the rod 15 by means of a pin 114 and the piston 13 is held in place 80 by a nut 113. Between the piston-rod 15 and the orifice in the upper wall of the cylinder 11 through which it slides, are provided packings, one of which is indicated at 16, so that a fluid-tight fit is afforded and leakage 85 from the upper end of the cylinder 11 past the piston-rod 15 is prevented.

In order to prevent angular movement of the piston-rod 15, the upper piston 14, at its lower portion, is formed with projecting 90 side ribs 29 which are received in correspondingly shaped portions in the cylinder 12, these portions being indicated at 30 in Figure 1.

The piston 14 is cut away on opposite 95 sides of a diameter, as shown at 17 and 18, to provide flattened surfaces. A removable jaw 19 is secured by means of undercut portions 20 and a bolt and retaining washer indicated at 21 in the piston 14 so that the 100 usual flared end of the jaw is presented in the flat surface of the cut away portion 18.

A companion jaw 22 is similarly secured by undercut portions 23 and a bolt and re-

taining washer indicated at 24 in the upper surface of the top of the cylinder 11. The jaws 19 and 22, as will be seen from the drawings, are formed with opposed semi-cylindrical recesses (to engage the shank of a drill-bit or the like) which both open into outwardly-flared portions.

In addition to the gripping jaw 22 swaging dies 33 are also mounted in the top of the cylinder 11 and in piston 14 alongside the gripping jaw. The swaging dies are held in place by means of plates 34 and bolts 35 which pass completely through the thickened upper portion of the cylinder 11 and through the portion 14 respectively in which the dies are mounted.

A sizing die 36 is provided and is held in position by means of clamping means 37. This sizing die is in the form of a gauge-rod 20 the position of the end of which in relation to the left-hand pair of swaging dies 33, can be adjusted to determine the diameter of the drill-bit. It will be understood that the gauge-rod is pushed forward so that its end 25 will engage the face of the drill-bit at a position along the taper of the swaging dies where the diameter of the dies at that position will be that required for the tool.

The meeting line of the jaws is on a level 30 with the axis of a reciprocating dolly hammer to which the general reference numeral 25 is applied. This dolly hammer is supported on a bracket 26 in a manner usual in machines of this sort, a spring 27, or a 35 spring of any other preferred form and disposition, being provided for returning the dolly to its inoperative position.

It will be seen that when compressed fluid such as compressed air is admitted above the 40 pistons 13 and 14, they mutually serve to close the jaw 19 on to the jaw 22 and in this way apply a strong holding pressure to a drill-bit or the like to be held between them.

For controlling the supply of compressed 45 fluid to the cylinders 11 and 12 a control valve, indicated at 28 in Figure 1, is provided but as the operation of the control valve is well understood and in itself forms no part of the present invention, it will not 50 be described in detail herein.

Adapted to engage the lower end of the piston-rod 15 but unconnected therewith is a piston 31 which slides in a cylinder 32 co-axially arranged in respect of the cylinders 55 11 and 12. In the cylinder 32 there is maintained a constant air-pressure, against which the piston 31 is moved when the jaw 19 is closed on to the jaw 22. This affords a return means for raising the pistons 13 and 14 60 when the valve 28 is moved to a position in which it will open the cylinders 11 and 12 to exhaust.

It will be seen that the top surface of the 65 upper wall of the cylinder 11 is formed with a thickened portion, the top surface of

which is shaped to conform to the shape of the opposed end of the piston 14. This is clearly illustrated in Figure 3.

Throughout the illustrations the means for securing the parts together are omitted, 70 for the sake of clearness, but it will be understood that wherever required bolts and nuts or other securing devices are provided to afford tight, sound joints between the various portions of the structure which require 75 to be rigidly attached one to the other.

What we claim as our invention and desire to secure by Letters Patent is:—

1. A forging machine of the type described comprising in combination two opposed work-holding jaws one at least of which is movable relatively towards and away from the other, a reciprocating forging hammer arranged to operate on the work while it is held by said jaws, a single piston-rod connected with the movable jaw, and two pistons and cylinders the pistons of which are both connected to said piston-rod and serve jointly to move said movable jaw towards the companion jaw, said pistons being arranged respectively on opposite sides of the said companion jaw, for the purpose described.

2. A forging machine of the type described comprising in combination two opposed work-holding jaws, one at least of which is movable relatively towards and away from the other, a reciprocating forging hammer arranged to operate on the work while it is held by said jaws, a single piston-rod connected with the movable jaw, a plurality of co-axially arranged pistons and cylinders, which pistons are respectively connected to said piston-rod at opposite sides of said companion jaw and serve jointly to move said movable jaw in one direction, and another piston and cylinder whereof the piston is disconnected from the piston-rod and serves to move the latter in a direction reverse to that in which it is moved by the first-mentioned pistons.

3. A forging machine of the type described comprising in combination two opposed work-holding jaws one at least of which is movable relatively towards and away from the other, a reciprocating forging hammer arranged to operate on the work while it is held by said jaws, a single piston-rod connected with the movable jaw, two pistons and cylinders the pistons of which are respectively connected to said piston-rod at opposite sides of said companion jaw and serve jointly to move said movable jaw towards its companion jaw, and another piston and cylinder the piston of which is arranged to operate said piston-rod and serves to return the piston-rod and the movable jaw to the open position.

4. A forging machine of the type described comprising in combination two op-

posed work-holding jaws one at least of which is movable relatively towards and away from the companion jaw, a reciprocating forging hammer arranged to operate on the work while it is held by said jaws, a single piston-rod connected with the movable jaw, two pistons and cylinders the pistons of which are respectively connected to said piston-rod on opposite sides of said 5 companion jaw and serve jointly to move said movable jaw towards its companion jaw, another piston which is arranged to coact with said piston-rod and serves to return the piston-rod and the movable jaw to the 10 open position, and a closed air-chamber constituting a cylinder for the last-mentioned piston, and means to maintain a permanent air-pressure within said air-chamber, for the purpose described.

20 5. A forging machine of the type described comprising in combination two opposed work-holding jaws one at least of which is movable relatively towards and away from the other, a reciprocating hammer arranged to operate on the work while it is held by said jaws, a single piston-rod connected with the movable jaw, and two pistons and cylinders the pistons of which are both connected to the said piston-rod 25 and serve jointly to move the said movable jaw towards its companion jaw, the said pistons being arranged respectively one above and one below the said companion jaw and the upper piston having a cut-back 30 portion to afford a flat on a side wall of the piston for the purpose described.

6. A forging machine of the type described comprising in combination two opposed work-holding jaws one at least of which is 40 movable relatively towards and away from the other, a reciprocating forging hammer arranged to operate on the work while it is held by said jaws, a single piston-rod connected with the movable jaw, and two pistons and cylinders, the pistons of which are both connected to the said piston-rod and serve jointly to move the said movable jaw 45 towards the companion jaw and are disposed respectively above and below the said companion jaw, the latter being located in an upper wall of the lowermost of the said two cylinders.

7. A forging machine of the type described comprising in combination two opposed work-holding jaws one at least of which is movable relatively towards and away from the other, a reciprocating forging hammer arranged to operate on the work while it is held by said jaws, a single piston-rod connected with the movable jaw, and two pistons and cylinders both of which pistons are connected to the said piston-rod 55 and serve jointly to move said movable jaw towards the companion jaw, the pistons being arranged respectively one above and one

below the companion jaw and the latter being located in an upper wall of the lowermost cylinder, the surface of that wall being shaped to conform to that of the opposed surface of the upper piston.

8. A forging machine of the type described comprising in combination two opposed work-holding jaws one at least of which is movable relatively towards and away from the other, a reciprocating forging hammer arranged to operate on the work while it is held by said jaws, a plurality of pistons and cylinders, means to operatively connect all the said pistons to the movable jaw, laterally projecting ribs 70 formed on at least one of the pistons to afford an unbroken lateral surface and correspondingly shaped recesses in the cylinder in which that piston works to receive said ribs 75 for the purpose described.

9. A forging machine comprising in combination a pair of opposed work-holding jaws one at least of which is movable relatively towards and away from the companion jaw, two pistons and cylinders the 80 pistons of which are arranged respectively above and below the said companion jaw, a single piston-rod operatively connected to both said pistons and to said movable jaw, the latter being located in the lower face of 85 the upper piston, and the companion jaw located in an upper wall of the lower cylinder.

10. A forging machine comprising in combination two opposed work-holding 90 jaws one at least of which is movable relatively towards and away from the other, and a plurality of co-axially arranged pistons and cylinders the pistons of which are all operatively connected to the said movable jaw and serve jointly to move it towards the companion jaw, two of which pistons are respectively situated at opposite 95 sides of the latter jaw.

11. A forging machine comprising in combination two opposed work-holding 100 jaws one at least of which is movable relatively towards and away from the companion jaw, a plurality of co-axially arranged pistons and cylinders the pistons of 105 which are all operatively connected to the said movable jaw and serve jointly to move it towards the companion jaw, a co-axially arranged return piston and cylinder, which return piston is arranged to operate said 110 movable jaw and serves to return the latter to the open position and is situated at the side of the companion jaw remote from the movable jaw.

12. A forging machine of the type described comprising in combination two opposed work-holding jaws one of which at 115 least is movable relatively towards and away from the companion jaw, a plurality of co-axially arranged pistons and cylin- 120

ders, whereof one piston is situated at one side and another piston is situated at the opposite side of said companion jaw, a single connecting rod operatively connected with each said piston and with the said movable jaw whereby all said pistons serve to move said movable jaw towards its companion jaw.

13. A forging machine comprising in combination a pair of work-holding jaws one of which at least is movable towards and away from the companion jaw, two co-axially arranged pistons and cylinders the pistons of which are arranged respectively above and below the said companion jaw, a single piston-rod operatively connected to both said pistons and to said movable jaw, the latter being located in the lower face of the upper piston and the companion jaw located in an upper wall of the lower cylinder.

14. A forging machine of the type described comprising in combination two opposed work-holding jaws vertically arranged one above the other, a reciprocating forging hammer arranged to operate on one

end of the work while it is held by said jaws, two pistons and cylinders co-axially arranged one above the other with one of the jaws located in an upper face of the lower cylinder and the other jaw located in the lower face of the upper piston, a single piston-rod on which both said pistons are mounted, laterally-projecting ribs on the upper piston, and correspondingly shaped recesses in the outer cylinder to receive said ribs, a third piston at the lower end of said piston-rod, and a third co-axial cylinder for said piston, means to maintain a constant air-pressure within said third cylinder, co-operating swaging dies in the opposed jaw-faces, the upper piston being formed with a flattened surface so as to afford a clearance for securing devices for holding the said swaging dies in position therein.

45 In testimony whereof we have signed our names to this specification.

ARTHUR TREVE HOLMAN.
KENNETH JAMES HOLMAN.
